UNITED STATES PATENT OFFICE.

FREDERICK HORSTMANN, OF ASHLAND, KENTUCKY, ASSIGNOR OF ONE-FOURTH TO
W. A. HOOD, OF ASHLAND, KENTUCKY.

GRAIN SCOURER OR CLEANER.

1,074,052.

Specification of Letters Patent. Patented Sept. 23, 1913.

Application filed March 8, 1913. Serial No. 753,061.

To all whom it may concern:

Be it known that I, FREDERICK HORSTMANN, a citizen of the United States, residing at Ashland, in the county of Boyd and State of Kentucky, have invented new and useful Improvements in Grain Scourers or Cleaners, of which the following is a specification.

This invention relates to grain scourers or cleaners, and the primary object of the same is to provide a comparatively simple mechanism for separating the dust as well as the smut and other dirt from wheat or analogous grain and to carry on the scouring or cleaning operation of the grain without permitting the dust or dirt to mingle or remain in association therewith.

A further object of the invention is to provide a grain scouring or cleaning machine having adjustable features to regulate the operation of the machine relatively to the grain or to effect a light or heavy scouring action, and, furthermore, to provide for a scouring action relatively to the grain by only a part of the machine in accordance with the primary condition of the grain or as effective cleaning of the grain may require.

With these and other objects and advantages in view the invention consists in the construction and arrangement of the several parts which will be more fully hereinafter described and claimed.

In the drawings: Figure 1 is a longitudinal vertical section through the machine. Fig. 2 is a transverse vertical section of the machine. Fig. 3 is a side elevation of a machine showing parts in dotted lines and the outlet flue or duct broken away. Fig. 4 is an end elevation of the machine. Fig. 5 is a detail sectional view on an enlarged scale of the feed box and a portion of one of the ribs and screen. Fig. 6 is a detail perspective view of the adjustable feed regulating slide. Fig. 7 is a detail sectional view showing the grain outlet and its communication with the outlet flue or duct together with adjacent parts of the machine.

The numerals 5 and 6 designate cast metal sides which are sectional and separably associated at the center as at 7, the joint between the sections being coincident with the horizontal diameter of the machine. The sections 5 and 6 are supported on a suitable base 8 resting on the floor 9, the latter hav-

ing an opening 10 therethrough for a dust outlet 11 communicating with the bottom of the machine. The cast metal sides 5 are approximately circular in contour, the lower section being varied in its contour where it communicates with the dust outlet 11 so as to effect a practical egress of the dust and dirt from the grain. Between the sides 5 and 6 a sheet metal sheathing 12 is applied and secured to the side sections, sheet metal of suitable thickness being used for this sheathing to insure sufficient rigidity to the inclosure embodying the sides and sheathing. The sides 5 and 6 are formed with central air ingress openings 13, one in each, and secured to the said sides are bearing brackets 14 carrying suitable bearings 15 for the main or fan shaft 16 having on one end thereof a pulley 17 adapted to be driven from a suitable power source. As clearly shown by Fig. 3, the bearing brackets 14 comprise divergent arms extending outwardly from the bearings 15 and terminally secured to the sides 5 and 6 so as to avoid occlusion of the openings 13 as much as possible and at the same time provide a rigid shaft supporting means.

Within the casing composed of the sides 5 and 6 and sheathing 12 is a foraminous or wire gauze cylinder or screen 18 which is of materially less diameter than the interior of the casing, and between this cylinder or screen and the metallic sheathing 12 an annular dust chamber 19 is formed, the said chamber communicating at its lower portion with the dust outlet 11. This screen 18 has its opposite side edges held between joint ribs 18^a to form a positive association of the screen with the sides 5 and 6, especially when the latter are secured by tie rods 18^b which will be disposed at intervals in connection with said sides. Immediately inside and engaging the foraminous cylinder or screen 18 is a plurality of spiral ribs 20, 20^a, 20^b, 20^c, 20^d, 20^e and 20^f, continuing regularly around the cylinder or screen in spiral lines from right to left or from one side of the machine toward the opposite side, and within the ribs and at a suitable distance therefrom is a fan 21 mounted upon and keyed to the shaft 16 and having a plurality of radial arms or spokes 22 connected to a rim 23 having a series of fixed outstanding blades 24 and a corresponding number of adjustable blades or vanes 25, the

blades or vanes 24 and 25 being held by the rim 23 at regular intervals and constituting the means for driving the air through the grain and forcing the dust, smut and dirt outwardly through the foraminous cylinder or screen 18 into the chamber 19. By adjusting the blades or vanes 24 the air pressure upon the foraminous cylinder or screen 18 may be varied as may be desired and in accordance with the condition of the grain treated. Portions of the stationary blades or vanes 24 project inwardly from the rim 23 and the blades or vanes 25 are slotted as at 26 and engaged by bolts 27 passing therethrough and through the inwardly projecting portions of the blades or vanes 24, as shown by Figs. 1 and 2, and by loosening the bolts 27 the blades or vanes 25 may be moved outwardly relatively to the blades or vanes 24 or inwardly from the latter to decrease or increase the air pressure relatively to the screen as just explained.

As shown, the grain is admitted to the machine through a suitable feed pipe 28 which is located adjacent to the end of the shaft 16 having the pulley 17 thereon, the said pipe 28 connecting with an inlet chute 29 which opens into a feed box 30, shown in detail by Fig. 5. The feed box 30 has at its inner wall suitable guides or seats 31, and coöperating therewith is a slide 32, an opening 33 being formed through the foraminous cylinder or screen 18 at this point and the slide also having an opening 34 therein. The slide 32 has a handle 35 projecting through one extremity of the feed box exteriorly of the machine so that it may be readily adjusted, and an angular clip 36 is secured on the lower portion of the slide and engages the lower guide or seat 31 of the feed box, the upper edge of the said slide engaging the upper guide or seat 31 of said box. The slide 32 is also supported in its operative position by a lower strip 37 and an upper strip 38 which may be a part of the feed box. The slide coöperates with the channels 39, 40 and 41 between the one side of the casing and the ribs 20^a, 20^b and 20^c, the opening 33 being of such dimensions as to take in these channels or compartments between the ribs just specified and the slide may be adjusted to deliver the grain into either one of these channels when the grain may only require a partial operation of the machine thereon. By adjusting the slide 32 inwardly and outwardly the opening 34 is brought into registration with the different channels or compartments 39, 40 and 41 and the grain from the box 30 is thus directed into any one of the channels.

The slide 32, as will be understood, forms the inner wall of the feed box 30 and the opening 33 through the foraminous cylinder or screen extends in the direction of the feed box to facilitate the inflowing of the

grain. It will be seen that the grain when admitted to the first channel 41^a will be caused to pass through the entire series of channels by the action of the spiral ribs 20^a, 20^b, etc., which will tend to feed the grain transversely of the machine and in close contact with the foraminous cylinder or screen 18 so as to cause grain to thoroughly wash the latter in a thin sheet and the dust and dirt are thereby driven outwardly therefrom through the cylinder or screen 18 into the compartment 19, the grain being turned over as it is caused to move from one side of the machine to the opposite side thereof.

At the side of the machine opposite that having the inlet for the grain, an outlet chute or spout 42 is disposed and communicates with the last channel or compartment of the series of channels between the spiral ribs, the chute or outlet 42 being in the form of an elbow, as shown by Fig. 7, and communicating with an outlet spout or duct 43 which may extend off from the machine any suitable distance at an angle, as shown by Fig. 8.

To render the casing of the machine accessible at different points, a hand-hole 44 is formed in one side and normally closed by a slide 45, and at the lower part of the sheathing is a similar hand-hole 46 which is normally closed by a slide 47. The slides 45 and 47 may be readily opened at any time desired to permit the operator to insert the hand in the machine to regulate or adjust the blades or vanes 25 and to reach the slide or for other purposes.

In the operation of the machine the grain is fed into the box 30 through the pipe 28 and inlet duct or chute 29 and admitted into the channels between the ribs 20^a, 20^b, 20^c, etc., or to either one of the latter, and is thrown out against the inner side of the foraminous cylinder or screen 18 and spread in a thin layer and held in such position by the fan blades 24 and the air forced thereagainst the air, being blown through the grain and carrying the dust, dirt or smut outwardly through the foraminous cylinder or screen 18 into the chamber 19, the dust, dirt or smut passing off downwardly through the dust outlet 11 and the grain being gradually worked around and across toward the outlet spout 42 and from the latter passes into the outlet duct 43.

The improved machine will be found exceptionally advantageous in its operation in cleaning grain of all kinds and in expediting the effective elimination or separation of dust and dirt from the grain in accordance with the primary condition of the latter, and, furthermore, the parts of the machine are comparatively simple and may be easily reached for adjustment and repair.

The intensity of the air current may be

varied by speeding the machine either high or low and the grain is not broken or injured as it has light or limited contact with the fan blades owing to the action of the air driving the grain outwardly against the foraminous cylinder or screen. Furthermore, the grain will be maintained in the individual channels and will not be permitted to jump from one channel to another, and all 10 of the grain will therefore be subjected to the same relative cleaning period and action, with material advantages in effectively removing the dirt and dust from the grain.

What is claimed is:

15. 1. In a grain scourer or cleaner of the class specified, the combination of a casing, a fixed foraminous cylinder within the casing, a fan rotating within the cylinder, spirally arranged ribs extending around the 20 interior of the cylinder and forming longitudinally unobstructed spiral grain channels which cause the grain to move laterally of the scourer from the point of inlet toward the outlet, a dust chamber being formed between the outer portion of the cylinder and 25 the casing and having a bottom outlet, and means for feeding grain into the interior of the cylinder at different points.
  2. In a grain scourer or cleaner of the 30 class specified, the combination of a casing, a fixed foraminous cylinder within the casing, a fan rotating within the cylinder, spirally arranged ribs extending around the 35 interior of the cylinder and forming grain channels, a dust chamber being formed between the outer portion of the cylinder and the casing and having a bottom outlet, and means for feeding grain into the interior of the cylinder and embodying an adjustable 40 slide for controlling the admission of the grain to different channels between the ribs.
  3. In a grain scourer or cleaner of the 45 class specified, the combination of a casing, a fixed foraminous cylinder within the casing, a dust chamber being formed between the cylinder and the casing and provided with a bottom outlet, a plurality of spirally arranged ribs in the cylinder and bearing against the latter and forming a corresponding plurality of spiral channels extending 50 fully around the interior of the cylinder, a fan within the cylinder and ribs, means for feeding grain at one side to the interior of the cylinder to different spiral channels 55 without feeding preceding channels, and
- means for permitting the cleaned grain to emerge from the cylinder at a point opposite the inlet of the grain to said cylinder.
4. In a grain scourer or cleaner of the class specified, the combination of a casing, 60 a fixed foraminous cylinder within the casing, a plurality of spiral ribs extending fully around the interior of and bearing against the cylinder and forming spiral channels, a fan within the cylinder and ribs, 65 an outlet at the lower portion of the cylinder and communicating with the interior of the latter, and an inlet to the cylinder embodying a feed box having a slide constituting its inner wall, the slide being formed 70 with an opening to deposit the grain in either one of several of the spiral channels adjacent to the feed box.
  5. In a grain scourer or cleaner of the 75 class specified, the combination of a casing, a foraminous cylinder fixed within the casing and forming a dust chamber with the wall of the latter, the said dust chamber having a lower outlet, a plurality of spiral 80 ribs within the cylinder and forming spiral channels extending fully around the said cylinder, a fan within the interior of the cylinder and ribs, an outlet for the cylinder, and means for feeding grain to one side of the cylinder and different spiral channels 85 without feeding the preceding channel or channels.
  6. In a grain scourer or cleaner of the 90 class specified, the combination of a casing having a foraminous cylinder fixed therein, a plurality of spiral ribs extending fully around and engaging the interior of the cylinder and forming spiral grain channels, an outlet at the lower portion of the terminal channel, and means located at one side 95 of the cylinder at a point opposite and above the outlet for the terminal channel for feeding the grain into different spiral channels without feeding the preceding channel or channels and causing said grain to either 100 pass through a portion of the channels or all of the latter.

In testimony whereof I have hereunto set my hand in presence of two subscribing witnesses.

FREDERICK HORSTMANN.
